Saul Dushman,
Alfred G. Davis
His Attorney.

UNITED STATES PATENT OFFICE.

SAUL DUSHMAN, OF SCHENECTADY, NEW YORK, ASSIGNOR TO GENERAL ELECTRIC COMPANY, A CORPORATION OF NEW YORK.

PROTECTIVE DEVICE.

1,172,961.

Specification of Letters Patent.

Patented Feb. 22, 1916.

Application filed May 20, 1915. Serial No. 29,453.

To all whom it may concern:

Be it known that I, SAUL DUSHMAN, a subject of the King of Great Britain, residing at Schenectady, in the county of 5 Schenectady, State of New York, have invented certain new and useful Improvements in Protective Devices, of which the following is a specification.

My invention relates to the protection 10 against overload of devices passing a substantially constant current with a variable impressed voltage, such, for example, as incandescent cathode devices, which when operating in series with a load device are 15 liable to injury or destruction should the load device or devices be short-circuited or in any other way consume less voltage and thereby cause an excessive voltage across the constant current device.

20 Although my invention is of general application it may be better understood by a consideration of the electric characteristics of incandescent cathode electron discharge devices. When such a device is so highly 25 exhausted that its current is a pure electron discharge, relatively large amounts of energy may be transmitted. Over a given range, varying with the geometric relation in space of the parts of the discharge de-

30 vice, the distance between the electrodes and other factors, the current varies with the $3/2$ power of the voltage and then at higher voltages the current becomes substantially constant with a variable impressed voltage.

35 When the voltage impressed is greater than this critical value, the resistance of the external load may be varied without affecting the current. The latter then depends only upon the temperature of the source of elec-

40 tron discharge. During normal operation only a small part of the voltage of the source is consumed in the tube, the rest of the voltage being consumed in the load. Should the load be short-circuited all of the

45 voltage, and hence all of the energy of the system, would be consumed in the tube, and unless some safety device were provided the tube would be destroyed. Ordinary protective devices would not protect the tube

50 under these circumstances. In the first place, since the current remains constant, an excess current device would not operate. Secondly, an excess voltage device could not be used since the full voltage that occurs

short-circuit exists in normal operation on every other half cycle while current has ceased to flow because of the unidirectional conductivity of the tube. This high voltage that exists normally while current is not flowing does no harm to the tube since it represents no energy, but it makes impossible the utilization of the usual excess-voltage devices to protect the tube. 60

In accordance with my invention I utilize 65 the increase in voltage drop across the device to be protected to effect an increase of current passed by an auxiliary electron discharge apparatus when the current is of a polarity to cause a rise of energy in the main device. 70 This auxiliary device is constructed to require a high voltage to pass an appreciable current, and in which the current under normal operating conditions is considerably below the saturation value at which any further increase in voltage produces no further current. This increase of current in the auxiliary device actuates any known 75 form of current relay to deenergize the main discharge device, and also deenergizes the 80 auxiliary discharge device.

My invention will be better understood by reference to the following description taken in connection with the accompanying drawing in which—

85 Figure 1 illustrates my invention dia- grammatically in connection with a series load circuit supply by half wave rectifiers, and Fig. 2 illustrates by curves the relation of the voltage and the current in the main 90 and the auxiliary devices.

95 Referring to the drawing the main electron discharge device 1, which in this case is shown as supplying the load 2 with rectified current is connected to the secondary of a transformer 3, by the conductors 4, 5. The discharge device contains an incandescent cathode 6, and an anode 7. The electrodes are so completely freed from gas and the space in the envelop evacuated to a pressure so low 100 that transmission of energy occurs by pure electron conduction substantially without gas ionization. With this end in view the bulb is first evacuated by approved lamp exhaust methods, the last portions of gas being removed by the Gaede molecular pump or any other means capable of removing vapors of oil and water as well as gases. When the evacuation has proceeded to such a high degree that an electron discharge of 110

considerable magnitude may be sent through the device without destructive positive ionization, the cathode is heated to incandescence and a high potential, for example, 5 5000 volts and higher, impressed upon the electrodes. The bombardment of the anode by the electron discharge liberates therefrom ionizable gas. As soon as a blue glow is observed the discharge is discontinued and 10 pumping continued until a high vacuum has been restored when the process is repeated. When the electrodes have been thus sufficiently freed from gas to operate at high voltages without giving off gases and the 15 space within the tube has been exhausted to a vacuum of about .05 microns (0.00005 m. m. of mercury) or lower, the tube is sealed off from the pump. The cathode 6 is heated to incandescence by a battery 8 connected to the cathode by the conductors 9, 20 10, having in circuit a switch 11, the object of which will be presently explained. The electrodes of the device are spaced closely together so as to decrease the voltage drop 25 and consequent energy loss. The effect of this is to lower the voltage limit above which the device operates with a constant current with a variable impressed voltage.

As explained by Dr. Irving Langmuir in 30 the *Physical Review* for December 1913, the electrostatic and magnetic influence of each electron in a given space on every other electron in the space between the electrodes of the device is known as the "space charge" effect. Owing to this space charge effect the 35 electron current varies over a given range with the impressed voltage, providing the temperature of the filament is so high that there is no limitation owing to the inability 40 of the cathode to supply electrons. At voltages above this range the current remains substantially constant. As noted above, the 45 range of space charge voltage depends on the geometrical relations of the parts of the device. The device 1 is constructed to operate with a low "space charge" voltage to reduce to a minimum the loss of energy in the tube. For example, as shown in Fig. 2, the 50 electrical characteristic of the device may be represented by the curve A, the ordinates being current value in milliamperes, and the abscissæ voltage values. In this particular device with the filament at a given temperature the current increases with the 3/2 power 55 of the voltage up to 100 volts when all the electrons which the filament is capable of emitting at that temperature are utilized; at voltages exceeding 100 volts the current remains constant.

60 Connected across the terminals of the rectifier 1 is a second rectifying device 12, also having an electron-emitting cathode 13 and an anode 14. In this device the electrodes are so arranged, for example, by spacing 65 them more widely apart, that the range over

which the current varies with the voltage is very greatly increased, the range of voltage accompanied by a variable current including the working range of voltage drop across the terminals of the device 1.

70 Again referring to Fig. 2, the electrical characteristics of the device 12 may be represented by the curve B. The current increases with the 3/2 power of the voltage multiplied by a constant depending on the 75 electron emission up to nearly 600 volts, and then becomes substantially constant at 80 milliamperes, the electron emission being somewhat less than in the device 1, for example, because of a lower filament tempera- 80

The battery 15 heating the cathode 13 has included in its circuit conductors 16, 17, and a switch 18 connected to the same shaft 19 as the switch 11. In series with the device 12 is the winding of an electromagnet 20 having its core connected to the shaft 19. Under normal operating conditions the space charge voltage across device 1, and consequently across device 12, is so low that 90 the current passing through the device 12 is so small that it is insufficient to operate the magnet 20. On the other hand, when a short circuit or sudden decrease in resistance of the load occurs, the voltage across 95 both the devices 1 and 12 becomes so high that the current through device 12 becomes sufficiently great to cause the magnet 20 to raise its core, opening the switches 11 and 18, and closing the switch 23. In the given 100 case this tripping current might be set at 40 milliamperes. The effect of this is to deenergize the heating circuits of the cathodes of both the devices 1 and 12 by opening the switches 11 and 18 and to connect the winding of the magnet 20 across the battery 15 by the conductors 16, 21, and 22 by the closure of a switch 23. When the disturbing conditions have been corrected 105 the switches 11 and 13 may be closed and 110 the switch 23 opened in any suitable way, for example, by opening a switch 24 in the circuit 16.

What I claim as new and desire to secure by Letters Patent of the United States, 115 is:—

1. The combination of a source of alternating current, an electron discharge device, conducting a constant current with a variable impressed voltage exceeding a predetermined value, connected to said source, a load connected in series with said device, an auxiliary electron discharge device conducting a variable current at an impressed voltage exceeding the predetermined operating voltage of the first device, and means responsive to a predetermined rise of current in the second device to deenergize the first discharge device. 120

2. The combination of a discharge device 130

- having an electron-emitting cathode and being evacuated to a pressure so low that conduction of energy occurs substantially without positive ionization, a load connected in series with said device, a source of alternating current connected to supply current to said device and said load at a voltage exceeding the voltage at which the current of said device becomes substantially constant, a second pure electron-discharge device connected in parallel with the first device constructed to operate with a variable current over a voltage range exceeding the range of voltage over which the current is variable in the first device, and means responsive to a predetermined rise of current in said second device to deenergize both of said devices.
3. The combination of an electrical discharge device operating with a substantially constant current over a variable range of impressed voltage exceeding a predetermined value, a load in series with said device, rectifying means connected in parallel with said device, transmitting current of the same polarity as said discharge device, the current being variable with the voltage

above the voltage value at which the current in said device is substantially constant and an electroresponsive device operatively connected to said means for deenergizing said discharge device upon a predetermined rise of current in said rectifying means.

4. The combination of a rectifier operating with a substantially pure electron discharge and having electrodes spaced closely to keep the energy loss due to space charge voltage drop at a low value, a second rectifier operating with a substantially pure electron discharge having electrodes spaced more widely apart to give a high space charge voltage, and connected to corresponding electrodes of the first rectifier, a source of electrical energy supplying said rectifiers, a load in series with both said rectifiers and an electroresponsive device operatively connected to said second rectifier for deenergizing both said rectifiers upon a predetermined rise of current.

In witness whereof, I have hereunto set my hand this 18th day of May, 1915.

SAUL DUSHMAN.
